CHARLES W. McLEOD

UNITED STATES PATENT OFFICE.

CHARLES W. McLEOD, OF MICHIGAN CITY, INDIANA.

FENCE-POST.

1,236,095.

Specification of Letters Patent.

Patented Aug. 7, 1917.

Application filed August 10, 1916. Serial No. 114,222.

To all whom it may concern:

Be it known that I, CHARLES W. McLEOD, a citizen of the United States, residing at Michigan City, in the county of Laporte and State of Indiana, have invented certain new and useful Improvements in Fence-Posts, of which the following is a specification.

This invention has relation to new and useful improvements in a fence post and has for its primary object, the provision of the plastic post which will be provided with wire strand receiving openings between reinforced portions and a removable rod engaged in reinforced portions to hold a wire strand in each of the recesses.

Another object of the invention resides in the provision of novel reinforcing members having rounded corner portions located in extensions of one edge of the post and a rod engaged through said extensions and the reinforcing members to intersect recesses between said extended portions to retain wire strands in said recesses and in binding engagement with the inner walls of the latter.

For a further object the invention contemplates the provision of a fence post of the above stated character which will be of simple construction, durable and highly efficient in use.

With these general objects in view and others that will appear as the nature of the invention is better understood, the same consists in the novel combination and arrangement of parts hereinafter more fully described, illustrated in the accompanying drawings, and pointed out in the appended claims.

In the drawings forming a part of this application and in which like-designating characters refer to corresponding parts throughout the several views:

Figure 1, is a front elevation of the improved fence post in use.

Fig. 2, is an enlarged horizontal section on the plane of line 2—2 of Fig. 1.

Fig. 3, is a similar view on the plane of line 3—3 of Fig. 1, and

Fig. 4, is an enlarged perspective view of one of the reinforcing members.

Referring more in detail to the drawings, 1 designates the post proper which is preferably formed of a plastic material and which is of substantially triangular form in cross-section with its forward vertical edge

or corner 2 rounded and provided with spaced transverse wire strand receiving recesses 3 having concaved inner walls 4. By providing the recesses 3, the projections 5 are provided between the same and said projections 5 are reinforced as will be later described.

In order to properly reinforce the post proper 1, I provide a plurality of resilient reinforcing members 6, composed of metallic strips bent into substantially triangular form with the ends of these strips slightly spaced apart, as shown in Figs. 3 and 4. The metallic strips are preferably bent so that the ends of the same form one side of the triangle while the central portion of the strips form the opposite corner of the triangle, which corner is extended and rounded as shown at 7. The reinforcing members are placed in the mold in such manner that the corners 7 thereof will project into the extensions 5, as shown in Fig. 3 and thereby reinforce and strengthen the same.

After the wire strands of a fence have been placed in the recesses 3, the removable rod 9 is forced downwardly through the extensions 5 and in front of said wire strands 8 to retain the latter in binding engagement with the concaved inner walls 4 of said recesses 3, as clearly shown in Fig. 2, thereby preventing longitudinal movement of said strands 8. It will be understood that the rod 9 is of sufficient length to intersect all of the recesses 3 and said rod should be provided with a head 10 which may be produced by bending the upper end of said rod, as shown in Fig. 1.

The advantages of this form of post will be readily apparent and further description of the same is believed to be unnecessary.

While the form of the invention herein shown and described is what is believed to be the preferred embodiment thereof, it is nevertheless to be understood that minor changes may be made therein without departing from the spirit and scope of the invention as claimed.

What I claim as new is:

1. A plastic fence post comprising a post proper of triangular form with one corner rounded and having transverse recesses with concaved inner walls, reinforcing members within said post proper and having portions extended between said recesses, and a rod passed through the reinforced projecting

portions of said post proper and intersecting the recesses to retain wire strands in binding engagement with said inner walls.

2. A plastic fence post comprising a post proper formed of plastic material and having a rounded edge, a plurality of resilient split reinforcing members position in said post proper and bent to substantially conform to the exterior contour of said post proper, said post proper having recesses formed in said rounded edge between said reinforcing members, and a rod extended through said post proper and said reinforcing members, said rod intersecting said recesses and serving to retain wire strands in engagement with the inner walls of said recesses.

3. In a plastic fence post, a body having spaced wire strand receiving recesses therein, the recesses defining extensions therebetween, substantially triangular shaped mem-

bers embedded in the body and having their apices embedded in the extensions, and means extending longitudinally through the extensions and recesses for retaining the wire strands in position.

4. In a plastic fence post, a plastic body having alined notches formed in one face thereof which define extensions therebetween, reinforcing substantially triangular shaped elements embedded in the plastic body, the apices of which extend within the extensions, and a removable wire retaining rod extending longitudinally through the extensions and recesses.

In testimony whereof I affix my signature in presence of two witnesses.

CHARLES W. McLEOD.
